CLOTHESLINE PROP

Sidney O. Orthwin, Dayton, Ohio, assignor to
Orco Products, Inc., Dayton, Ohio, a corpora-
tion of Ohio

Application February 27, 1950, Serial No. 146,461

1 Claim. (Cl. 248—353)

1

This invention relates to clothesline props.

An object of this invention is to provide an extensible clothesline prop together with an improved means for securing the line to the prop so that the line will not become disengaged from the prop.

In one form of this invention a pair of elongated strips of wood are disposed in face abutting relation and adjustably secured together by means of a U-shaped clamp and a slide, the clamp being fixed to one strip with the slide fixed to the other strip. One of the strips is formed with a fork or slot in its outer or upper end for receiving the clothesline, and the line and upper strip are clamped together by means of a clothespin which engages through a transverse opening intersecting the slot. The clothesline is clamped to the clothespin so that the prop and the line are secured together.

In another form of this invention a tapered wedging pin is used to clamp the line and prop together.

With the above and other objects in view, my invention consists in the arrangement, combination and details of construction disclosed in the drawings and specification, and then more particularly pointed out in the appended claim.

In the drawings:

Figure 1 is a detailed side elevation of a clothesline prop constructed according to an embodiment of this invention.

Figure 2 is a sectional view partly in elevation and broken away taken substantially on the line 2—2 of Figure 1.

Figure 3 is a sectional view taken on the line 3—3 of Figure 2.

Figure 4 is a sectional view taken on the line 4—4 of Figure 2.

Figure 5 is a sectional view taken on the line 5—5 of Figure 2.

Figure 6 is a fragmentary sectional view taken on the line 6—6 of Figure 2.

Figure 7 is a detailed side elevation partly broken away showing a modified form of this invention.

Figure 8 is a fragmentary sectional view showing another modified form of clamping the clothesline to the upper stick of the prop.

Figure 9 is a fragmentary sectional view taken on the line 9—9 of Figure 8.

Figure 10 is a fragmentary sectional view taken on the line 10—10 of Figure 9.

Figure 11 is a fragmentary perspective view of the upper end of the prop shown in Figures 1 to 6, inclusive.

2

Referring to the drawings, and, first, to Figures 1 to 6, inclusive, the numerals 10 and 11 designate generally upper and lower prop forming sticks which are disposed in face abutting relation. The lower stick 10 is formed with a point 13 adapted to project into the ground, and the upper end of stick 11 is formed with a slot 12 within which a clothesline 14 is adapted to loosely engage. The upper stick 11 is formed with a transversely extending opening 15 which intersects the slot 12 and a clothespin 16 is extended through the opening 15 and is adapted to have the clamping arms 17 thereof engaged about the clothesline 14.

The two prop forming sticks 10 and 11 are adjustably secured together by means of a U-shaped clamp 18 which is secured by fastening means 19 to the lower stick 10. The clamp 18 has a bolt 20 extending through the parallel arms thereof, and a wing nut 21 is threaded onto the bolt so that tightening of the nut 21 will effect a clamping of the two sticks 10 and 11 together.

A U-shaped slide member 22 is secured by fastening means 23 to the upper stick 11 adjacent the lower end of the latter, and the parallel sides of the U-shaped slide 22 are formed with inwardly projecting flanges 24 which engage on the outer side of the lower stick 10.

Referring now to Figure 7, there is disclosed a modified form of clamping means for clamping the two endwise adjustable prop forming sticks 10a and 11a together. A pair of clamps 18a and 18b are secured one to each of the sticks 10a and 11a and are adapted when in clamping position to tightly hold sticks 10a and 11a against endwise movement.

Referring now to Figures 8 and 9, there is disclosed another means for clamping the clothesline to the upper end of the upper stick. A tapered wedging pin 25 is extended through the openings 15c in the upper end of the upper stick 11c so as to wedge the line L in the lower portion of the opening 15c.

In the use of this invention the prop formed by the two sticks 10 and 11 is adjusted as to length so as to stretch the clothesline 14 as may be desired or to hold the clothesline so that the clothes will not drag or touch the ground. The line 14 is then firmly clamped to the upper end of the upper stick 11 by inserting a clothespin 16 through the opening 15 so that the clamping arms 17 of the clothespin will tightly grip the clothesline. It will, of course, be understood that, if desired the line may be initially clamped to the upper end of the upper stick 11 and then

the two sticks adjusted endwise as may be desired.

What is claimed is:

A clothesline prop having a slot in the outer end thereof for loosely receiving a clothesline and having a transversely circular opening therethrough intersecting said slot, and a forked clamping member having resilient legs extended through said opening and clampingly engageable with said clothesline between said resilient legs. 10
SIDNEY O. ORTHWIN.
